AUTOMATIC RURAL MAILBOX SIGNAL

Lawson Price, Rensselaer, Ind.

Application May 18, 1950, Serial No. 162,767

1 Claim. (Cl. 232—35)

1

This invention relates to rural mail boxes, and the main object thereof is the provision of a signal therefor which is automatically operated and moved into visible or signalling position when the door of the box is opened by the mail carrier prior to his placing the mail therein. Thus, without any other operation on the part of the carrier than that of opening the door of the mail box, the signal to the box owner is automatically set so that the latter may see at a glance whether or not there is any mail for him.

The above broad as well as additional and more specific objects will be clarified in the following description, wherein characters of reference refer to like-numbered parts in the accompanying drawing.

Referring briefly to the drawing, Fig. 1 is a perspective view showing a rural mail box having the automatic signal of this invention applied thereto.

Fig. 2 is a sectional view taken on the line 2—2 of Fig. 1, illustrating the automatic dropping of the signal to visible position upon opening of the mail box door.

Fig. 3 is a perspective view of the mail box, showing how it appears, with the signal in fully extended visible position, after the carrier has closed the door after placing mail in the box.

Fig. 4 is a sectional view taken on the line 4—4 of Fig. 1.

Referring in detail to the drawing, the numeral 10 indicates a rural mail box comprising the elongated housing 11 open at the front end, provided with the floor 12. A door 13 is hinged on a horizontal axis below the front open end of the box, as shown at 14, and cooperating spring clips 15 (on the housing 11) and 16 (on the door) serve as readily releasable means for maintaining the door in vertical or closed position.

The side walls 17 of the housing 11 extend downward below the level of the floor 12 to provide opposed longitudinal flanges under the box. Pivotal mounted on a horizontal axis on aligned pins 18 in the said flanges below the floor 12 and near the open forward end of the housing, a plate-like signal member is provided at 19. The signal 18 is normally adapted to be positioned, by gravity, in vertical suspension from its pivots 18. The free end of the signal 19 has a partly doubled-back forward edge providing a lip 20.

Intermediate the width and height of the door 13, a resilient band or member 21 is secured to the door and has its lower end 22 free and extending outward at an acute angle to the plane

of the door. With the door 13 closed, the signal 19 is swung into horizontal position and the lip 20 engages and depresses the free extension 22 of the member 21. The latter operation is performed by the mail box owner after he has removed the mail. Then, when the box is empty, the signal is invisible under the floor of the box, as shown in Fig. 1. When the carrier opens the door 13, as obvious in Fig. 2, the signal 19 is released to fall into the visible position shown in Fig. 3.

I claim:

A rural mail box comprising a housing open at the front end and having a floor, said housing including opposed side walls extending below said floor thereby providing longitudinal flanges under the box, a door hingedly mounted on a horizontal axis extending substantially across the lower edge of said front end of the box and adapted normally to be positioned vertically against said open end of the box, releasable means for maintaining said door in vertical position as aforesaid, a signal comprising a normally horizontal plate-like member having one end thereof pivotally mounted on a horizontal axis between said flanges, said last-named axis being positioned rearward of said open end of the housing, said signal being urged by gravity into vertical position of suspension from said last-named axis, and means partly on said signal and partly on said door for releasably locking said signal in horizontal position after manual swinging of the signal to horizontal position and after said door is closed, said means comprising a doubled-back lip on the free end of said member extending outward from the normally upper side of said member, said door having a member secured thereto on the outer surface thereof, said door member having an extension extending at an acute angle to the plane of the door in a downward direction, said lip being engageable by said extension when said door is closed and said signal is positioned horizontally as aforesaid.
